UNITED STATES PATENT OFFICE.

JOHN MOSIMAN, OF SEDALIA, MISSOURI.

WORK-BENCH.

1,149,671.

Specification of Letters Patent. Patented Aug. 10, 1915.

Application filed May 18, 1914. Serial No. 839,399.

To all whom it may concern:

Be it known that I, JOHN MOSIMAN, a citizen of the United States, residing at Sedalia, in the county of Pettis and State of Missouri, have invented a new and useful Work-Bench, of which the following is a specification.

The invention relates to improvements in work benches.

The object of the present invention is to improve the construction of work benches and to provide a simple, practical, and comparatively inexpensive work bench, designed for house carpenters, cabinet makers, and the like, and capable of compactly folding to enable it to be taken to and used in houses and other places where it is impossible to take an ordinary work bench.

A further object of the invention is to provide a foldable work bench of this character, which will be capable of being arranged in a solid condition for use.

With these and other objects in view the invention consists in the construction and novel combination of parts hereinafter fully described, illustrated in the accompanying drawings, and pointed out in the claim here-to appended, it being understood that various changes in the form, proportion, size and minor details of construction, within the scope of the claim, may be resorted to without departing from the spirit or sacrificing any of the advantages of the invention.

In the drawings:—Figure 1 is a longitudinal sectional view of a work bench constructed in accordance with this invention, and shown arranged for use. Fig. 2 is a reverse plan view of the same. Fig. 3 is a reverse plan view, the work bench being folded. Fig. 4 is a transverse sectional view on the line 4—4 of Fig. 2. Fig. 5 is a detail perspective view of one of the bearing brackets, in which the legs are pivoted.

Like numerals of reference designate corresponding parts in all the figures of the drawings.

In the accompanying drawings, in which is illustrated the preferred embodiment of the invention, 1—1 designates foldable legs pivotally connected to and supporting the top 2 of a carpenter's work bench, but the improvements may be applied to any other form of bench, or to a table top, where it is desired to provide a foldable bench or table which may be set up in a perfectly solid condition for use. The legs 2 are each com-

posed of spaced side bars 3 connected near their lower ends by a transverse bar 4, and at their upper and intermediate portions by crossed, diagonally arranged bracing bars 5, 60 preferably constructed of light metal and having their upper and lower terminals 6 and 7 bent at an angle and bolted or otherwise secured to the inner faces of the spaced side bars of the legs. The side bars 3 and the transverse bars 4 are preferably constructed of stout wood, but they may be of any other suitable material, and the side bars 3, which have a slight upward and inward inclination, are pivoted at their upper ends in bearing brackets 8 by bolts 9 or other suitable pivots. The bearing brackets 8, which may be constructed of any suitable material, have spaced side flanges 10 to receive the legs and are provided with upper 65 outwardly extending attaching flanges 11, which are secured to the lower face of the top of the bench by screws or other suitable fastening devices. The side flanges 10, which are pierced by the pivot bolt 9, are shown in the accompanying drawings, (Fig. 5) formed from a single piece of metal bent at spaced points at right angles to form a connecting back portion 12, which is riveted or otherwise secured to a depending flange 80 13, formed integral with and arranged at right angles to the attaching flange 11. The connecting portion 12 and the depending flange 13 constitute the back of the bracket, but the latter may consist of a single casting, as will be readily understood. 90

The legs, which are foldable against the lower face of the top of the bench, are supported in an operative position by substantially U-shaped inclined braces 14, preferably constructed of metal and composed of spaced side bars and a flat connecting bar 15. When the table is set up for use, the legs are arranged at a slight inclination, and extend upwardly and inwardly, as clearly 95 illustrated in Fig. 1 of the drawings, and the backs of the brackets form stops for the legs and coöperate with the braces in maintaining a rigid connection between the legs and the top of the bench. The side bars of 100 the foldable braces are pivotally connected at their outer ends 16 to the inner faces of the side bars of the legs at the lower portions thereof by bolts 17 or other suitable fastening devices, and they are provided 105 near their upper ends 18 with quarter bends to arrange the flat faces of the outer ter- 110

5 minal portions of the side bars in planes at right angles to the planes of the side faces of the body portions of the side bars of the braces. The upper ends 18 are also bent at 10 an angle and are riveted or otherwise secured to the lower or outer faces of the flat transverse connecting bars 15, which are adapted to fit flat against the lower face of the top 2 of the bench.

15 10 The flat bars, which connect the upper or inner ends of the foldable braces, are provided with spaced apertures 19, which are adapted to be engaged by studs 20, arranged in pairs at opposite sides of the center of the top 2 and depending from the lower face thereof. The studs 20 may be secured to the top 2 of the work bench in any desired manner, and in arranging the work bench for use, the flat connecting bars 15 are 20 passed over the studs and are locked in engagement with the same by buttons 21, pivoted to the lower face of the top 2 adjacent to the transverse planes of the spaced studs and arranged to engage the flat bars 15, as 25 clearly illustrated in Fig. 2 of the drawings. The pivoted buttons frictionally engage the bars 15 and securely maintain the same in engagement with the studs. Any other suitable fastening means, however, may be employed for locking the foldable braces in engagement with the studs.

30 25 When it is desired to fold the bench the foldable braces are unfastened and disconnected from the studs of the top 2, and one of the foldable braces is passed through the space between the side bars of the other foldable brace, and the legs are swung inwardly against the lower face of the top 2 of the bench. The side bars of the foldable 35 40 braces converge slightly and the pivoted terminals of the side bars of one of the braces are arranged in spaced relation with the inner faces of the adjacent side bars of the leg to permit the side bars of the other brace to occupy a position exteriorly of them, as clearly illustrated in Fig. 3 of the drawings. The outer terminals, which are spaced from the legs, are preferably maintained in such position by sleeves 21^a, mounted 45 50 on the adjacent pivot bolts 17. The legs and the braces are maintained in their folded position by a centrally arranged pivoted button 22, secured to a central transverse block 23 by a screw 24 or other suitable fastening device, and adapted to be 55 turned to a position longitudinally of the top of the table to engage the transverse bars 4 of the pivoted legs. The centrally arranged button, which secures the legs and

the braces in their folded position, is adapted to be turned transversely of the top 2 to a position in alignment with the central block or cleat 23 for releasing the legs. The foldable legs and braces are adapted to be easily and quickly arranged in either their supporting or folded positions, and they are securely fastened in either position. When the work bench is folded it occupies a comparatively small space, and it may be conveniently carried into a house or other place 60 where it is impossible to convey an ordinary work bench. Also, when the work bench is set up for use, it forms a rigid structure, and there is no liability of it shaking or accidentally collapsing, owing to the thorough 65 bracing and rigid fastening of the legs.

70 The top of the work bench may be of any desired construction, and when the improvements are applied to a bench designed for 75 house carpentry, the top of the bench will be equipped with a front side vise 25 and a rear end vise 26. The rear end vise preferably carries a removable stop 27 and is designed to be used in connection with a sliding 80 adjustable stop 28, which may be arranged in flush relation with the top of the table, when not in use. The top of the bench may also be equipped with various other 85 devices for adapting the bench for different 90 uses, but as these devices do not constitute a portion of the present invention, a detail description thereof is unnecessary.

95 What is claimed is:—

In a device of the class described, the combination with a top provided at its lower face with spaced projecting studs located at opposite sides of the center of the top, legs pivotally connected with and foldable longitudinally of the top, substantially U-shaped braces arranged at an inclination and pivotally connected at their lower ends with the legs and provided at their upper ends with transverse portions adapted to fit flat against the top and provided with spaced apertures receiving the studs, and pivoted fastening devices mounted on the said top at points beyond the studs, said fastening devices being arranged to engage and lock the transverse portions of the 100 105 braces in engagement with the said studs.

110 In testimony that I claim the foregoing as my own, I have hereto affixed my signature in the presence of two witnesses.

JOHN MOSIMAN.
